UNITED STATES PATENT OFFICE.

ANDREW J. ENGLISH AND CHARLES J. HART, OF CINCINNATI, OHIO.

DESIGN FOR A TIRE-TOOL.

58,472.

Specification for Design.

Patented July 26, 1921.

Application filed March 9, 1921. Serial No. 450,965. Term of patent 3½ years.

To all whom it may concern:

Be it known that we, ANDREW J. ENGLISH, a citizen of the United States of America, and a resident of the city of Cincinnati, in the county of Hamilton and State of Ohio, and CHARLES J. HART, a citizen of the United States of America, and a resident of the city of Cincinnati, in the county of Hamilton and State of Ohio, have jointly invented a new, original, and ornamental Design for a Tire-Tool, of which the following is a specification, reference being had to the accompanying drawing, forming part thereof.

In the drawing:

The figure is a perspective view of the design for tire tool.

We claim:

The ornamental design for a tire tool, as shown.

Witness our hands at the city of Cincinnati, in the county of Hamilton and State of Ohio, this 23rd day of February, 1921.

ANDREW J. ENGLISH.
CHARLES J. HART.
